UNITED STATES PATENT OFFICE.

LEE R. BUSHYAGER, OF JEANNETTE, PENNSYLVANIA.

FAN AND PROPELLER.

Application filed March 11, 1926. Serial No. 93,885.

My invention relates to fans and propellers, and particularly to propellers such as are employed in aeronautics for driving and lifting air craft. The object of my invention is a fan or propeller blade which may at will be changed in blade-angle; that is to say, the angle at which the face of the blade extends, with respect to a plane perpendicular to the axis of propeller rotation. 5 The face of a propeller blade ordinarily is warped; that is to say, the blade angle, of maximum size at the base of the blade diminishes from the base outwardly toward the tip. In the practice of my invention I may 10 and preferably do make provision that, as the blade angle is changed, the rate at which that angle diminishes from the base outwardly toward the tip shall change also; if at the base of the blade the blade-angle be 15 large, the warping of the blade shall be relatively steep; if at the base of the blade the blade-angle be small, then the warping from the base toward the tip of the blade shall be relatively gentle. My invention further 20 contemplates change in camber; that is to say, in cross-sectional shape of the blade. Ordinarily a propeller blade is in cross-sectional shape concavo-convex, the curvature of the convex surface being on shorter radii 25 than that of the concave surface, and the concave surface constitutes the face of the blade. My invention contemplates the possibility of changing the curvature of the face of the blade, and, incidentally, of the back 30 of the blade correspondingly. The curvature of the face of the blade may, within given limits, be increased or diminished, and the blade in cross-sectional shape may become 35 plano-convex or doubly convex, as desired. 40 The accompanying drawings illustrate the invention in application to a propeller for an aeroplane. Fig. I is a view in section, on a plane through the axis of propeller rotation, and showing in longitudinal section one of the propeller blades. Fig. II is a 45 view in section, on a plane at right angles to that of Fig. I and perpendicular to the axis of rotation, and longitudinal with respect to the blade. The plane is indicated at II-II, 50 Fig. I. Fig. II is diagrammatic, in that no attempt is made to indicate in it either blade-angle or warping; the showing is as though the blade extended in a plane, perpendicular to the axis of rotation. Fig. III is a view 55 of the structure in side elevation. Figs. IV and V are views in section, on the planes re- spectively indicated at IV-IV and V-V, 60 Fig. VI is a diagrammatic showing, and in side elevation, of the assembly of spars which go to make up a propeller blade. Figs. VII and VIII show the propeller blade cover in cross-section and in elevation and illustrate an incidental detail of structure. Fig. IX is a diagrammatic illustration of a 65 certain essential detail.

The propeller shaft 1 carries, splined to it, a hub 2. Hub 2 is provided with a plurality of radially opening pockets 3, whose general shape and arrangement will be sufficiently understood by considering Figs. I, 70 II, and III. The orifice of the pocket, it will be noted, is in Fig. III shown to extend angularly with respect to a plane perpendicular to the axis of rotation. This feature, though not essential to the invention, will 75 be preferred.

The propeller blade is compound; it is made up essentially of a plurality of longitudinally extending spars 4. These spars, mounted at the base in a pocket 3 of the hub, 80 extend through the orifice in the pocket, and are extensible and retractile in such mounting; and in their extension and retraction, and by the particular means about to be described, the ends already indicated are at 85 attained.

Within the pocket the basal ends 41 of the spars 4 are strung upon a bar 5, and bar 5 is mounted by screw-thread connection upon a shaft 6, which shaft with respect to 90 the axis of propeller rotation extends radially; or substantially so. As shaft 6 is turned, the bar 5 is moved outward and inward, and the spars 4 are correspondingly extended and retracted. Figs. I and II show 95 two pockets 3, arranged each diametrically opposite the other, and this is a convenient arrangement. In this case a single shaft 6, oppositely threaded at opposite ends, may carry in the two pockets two bars 5, and these 100 two bars will in response to shaft rotation move simultaneously and oppositely, outward and inward. It will of course be understood that such diametrically opposite arrangement of pockets 3 is merely the adaptation of the invention to a propeller having oppositely extending blades; it will be understood that for each pocket 3 there may be a separate shaft 6; and that, if the blades 105 are not oppositely arranged, each pocket will have a separate shaft 6.

In the orifice of each pocket is set a

cradle 7, adapted to engage (through blocks 9) the edges of the seated spars and adapted to tip transversely on its bearing 71. The opposite rim of the orifice is adapted to engage the opposite edges of the seated spars 4. Preferably this opposite rim of the orifice carries blocks 8. The blocks 8 are adapted to tip on their bearings 81 in the direction of the length of the seated spars. 10 Each pair of blocks 8 and 9 engages the basal end 41 of one of the spars 4. As particularly indicated in Fig. VI, the basal ends 41 of the spars 4 are provided with upper and lower edges which are relatively inclined, and this relative inclination varies as between the spars which together make up a set. As shown in Fig. VI the basal end of the spar nearest the observer is of diminishing width from left to right, and the end 20 of the most remote spar is of increasing width from left to right, and the intermediate spars are in this respect graded from one extreme in shape to the other. Manifestly in this graded succession the base of 25 an intermediate spar will be of uniform width throughout its extent, or substantially so. The general characterization of the spars as having angularly disposed opposite edges will not on that account be misunderstood. A cross-section through the basal ends of the assembled spars (Fig. IV) presents an assembly of trapezoidal outline, and while on different planes of cross-section the opposite non-parallel sides of the trapezoid 30 vary in their relative inclination (on one plane the trapezoid becomes a parallelogram), on every cross-section the area of that trapezoid is constant. As the bar 5 moves out and in extending and retracting 40 the spars 4, cradle 7 rocks transversely on its bearing, and the effect is that the component spars of the propeller blade shift relatively, in parallel planes, transverse to the face of the blade. Such relative shifting of the spars effects change in the blade-angle.

It is preferable that the change in blade-angle effected by the means described should be most pronounced toward the base of the 50 blade and least toward the tip. Stated in other words, it is desirable that as blade-angle increases, warping should increase; and as blade-angle diminishes, the face of the blade should approach more nearly to a plane surface. This desirable characteristic of movement I achieve by further refinement of the means which in their more general features have been already described.

I have said of the upper rim of pocket 3 60 that it is advantageously provided with a set of tipping blocks 8. Manifestly for purposes hitherto described the bearing of the basal ends of the spars upon the upper rim of the pocket might be against a transversely extending knife-edge. But, particu-

larly for the further purposes just indicated, I prefer to employ blocks such as those shown, semi-circular in outline, engaging along their straight edges the edges of the spar ends and turning in curved seats 70 formed to receive them. The cradle 7 carries a corresponding series of semi-circular blocks 9, engaging the spar ends along their straight edges and tipping in curved seats 75 formed for them in the cradle. Manifestly if, as the spars move outward and inward, the blocks 9 which they engage be shifted and held in new but unyielding positions, the range through which the individual spar sweeps may be shifted, relatively to a plane 80 perpendicular to the axis of propeller rotation; and when, added to this, the tipping of cradle 7 is taken into account—a tipping transversely, on the bearing 71—it is manifest that as between the spars which together 85 make up the blade, the effective movement so far as concerns blade shape may be made more pronounced toward the base of the blade and less pronounced toward the tip. Accordingly, I provide for a proper control of the blocks 9 in their actual and relative positions. The blocks 9 are provided with notches 91 which extend from the periphery radially inward. A rod 94 extends when the parts are assembled through 95 the series of notches, and within each notch the rod 94 carries an eccentric disk 92, and the disk engages the opposite parallel walls of the notch. The rod 94 being secure, the 100 blocks 9 are secure against tipping on their semi-circular seats 73 in cradle 7; and, as rod 94 is rotated on its axis the blocks 9 are tipped. In operation, as each block 9 is tipped, its opposite companion block 8 is tipped, and then, as the spar which lies between moves inward and outward (the transverse tipping of cradle 7 on its bearing 71 permitting this), its actual range is changed, relatively to any given plane perpendicular 105 to the axis of propeller rotation. The positions of the cam disks 92 upon the rod 94 are individually adjustable, but when adjusted the set of cams moves as a unit, rotating upon the axis of rod 94. The relative positions of the disks 92 in their adjustment 110 determines the ranges of movement of adjacent spars in relation one to another.

The rod 94 is journalled for rotation in the end walls of cradle 7 and at one end it is prolonged in a crank arm 93 which enters 115 a guiding groove 31 in the inner wall of pocket 3. The groove 31 is so particularly disposed that as the cradle is rocked transversely on its bearing 71 the rod 94 is rotated, and the disks upon the rod 94 are so particularly placed that the desired relative adjustment is got of the blocks 9 which make up the set.

The relative adjustment of the disks 92 upon the rod 94 determines the relative po- 120 125 130

sition of the ranges of movement of adjacent spars; and, as I have said, the adjustment is preferably such that as the blade-angle increases, warping increases. The groove 31 5 is spiral with respect to the axis of tipping of cradle 7 on its seat 71, and as this spiral is formed steep or gentle in its inclination the effect described will be more or less pronounced.

10 Change in camber, that is to say, in cross-sectional shape of the blade, may be effected as the spars are extended and retracted. In this connection reference is made to Fig. IX, in comparison with Fig. I. It will be perceived that if the lower edge of the basal portion 41 of spar 4 be engaged by block 9, and if at any given instant in operation block 9 be fixed as against tipping in its bearing in cradle 7, then it is the angle at 15 which the lower edge of the base 41 of the spar 4 extends, with respect to the mid-line $a-b$ of the spar, that is determinative of the range of sweep of the spar in a plane transverse to the face of the blade. And it will be perceived that accordingly as this angle varies, as between successive spars so the ranges of successive spars will vary in their relative positions; and, further, variation here may be such as to effect change 20 in camber.

25 Turning now to Fig. VI, it will be perceived of the collocation of spars there shown, that whereas at the mid-point in the length of the bases 41 all the spars lie in a straight line and in line with the eye, at the extreme right-hand end the succession is not on a horizontal line, nor is the line straight. The indication is that the middle spar of the series is most steeply inclined from left to right, and that the spars on either side are inclined at diminishing steepness to the outer ones. Viewed at the end this assembly 30 would be seen to be bowed downwardly along the lines defined by the upper and lower edges of the spars. Supposing the assembly to be otherwise such that a straight and unbowed succession would afford the desired shift of blade-angle without change in camber, then such a modification in the relative angularity of the bases of the blades as 35 would give the downwardly bowed assembly indicated in Fig. VI, would result in change in camber, superadded to change in blade-angle as the spars are extended and retracted. Furthermore, if the assembly were such as to produce no change in blade-angle, still the modification here alluded to 40 would afford change in camber by extension and retraction of the spars, while the blade-angle continued constant.

45 The drawings show the spars to be tapered, from base to tip, and it will be understood that by the particular relative positions given to the succeeding eccentric disks 92 on the rod 94, relatively great move-

ment at the bases and relatively little movement at the tips of the spars, may be attained, thus refining upon both the changes in blade angle and the changes in camber explained above.

To recapitulate, there are two variables in the organization: (1) the relative setting of the successive disks 92 eccentrically upon rod 94, and (2) the value of the angle which the lower edge of the blade forms with its mid-line. Warping may be controlled by the first of these variables; camber by the second. Underlying both is the characteristic that, given a set of spars with bases of graded angularity as between opposite edges, and given such a set of spars seated in a hub pocket with the tipping cradle 7 defining one edge of the orifice, change in blade-angle may be effected by the extension and retraction of the assembly of spars. And it is a mere matter of proper proportioning, what the range in such blade-angle change may be; it may, indeed, be reduced to zero, and will be, in case change in camber alone were in any particular case desired.

It remains to describe the means by which the shaft 6 is rotated, to effect the extension and retraction of spars 4 and the consequent changes in blade configuration. Shaft 6 carries a worm gear wheel 61, and to worm wheel 61 a worm 62 is meshed. Worm 62 in turn is geared by such intermediate parts as are illustrated in Figs. III, IV, and V, and which do not require particular enumeration, to the clutch device which includes two toothed sleeves 63 and 64 mounted upon hub 2 and connected by intermeshing pinions 65, and a swinging latch 66 under the control of the driver adapted to engage one or the other of sleeves 63 and 64 or to remain free of engagement with either.

So long as the latch 66 continues in the intermediate position shown in Figs. III, IV, and V the sleeves 63 and 64 will be carried without relative movement upon the rotating hub 2; the gearing described will be at rest, shaft 6 will not rotate and the blade will continue constant in shape. When, however, the latch 66 is swung to engage one or the other of sleeves 63 and 64, the rotation of shaft 1 will through the gearing described effect rotation of shaft 6 in one direction or the other. Spars 4 will correspondingly be extended or retracted, and the blade-angle will be changed, and with change in the blade-angle the degree of warping will preferably, and by the particular means described, be changed. And, in addition, and if desired, and by the particular means described, the camber also of the blade may, concurrently with the change in blade-angle, be changed.

When in such manner the shape of the blade has been altered in the desired manner and to the desired extent, the driver shifts the

latch 66 to intermediate position again, and thereafter the propeller blade remains in the particular shape to which it has thus been newly brought.

5. Fig. II shows, somewhat diagrammatically, some of the spars 4 which compose the propeller blade lying closely adjacent one another and others spread apart and with basal ends 41 radiating slightly. Blocks 72 19 may serve to maintain them in such position. If that radiating feature be present it is manifest that as the spars are extended not only will the angle, camber, and warping of the blade be changed but the breadth of the blade will simultaneously be increased.

20 The blade may consist of the assembly of spars and nothing more, or it may be provided with a cover. The cover, if it be present will be secured immediately to the spars, or its opposite webs will be so stayed together at intervals as to secure it in place upon the spars, and in any case suitable allowance will be made for changes in shape 25 of the assembly of spars within the cover. Figs. VII and VIII show a cover adapted 29 to a blade capable of being changed in width at the base by means such as have been described, the change in width diminishing 33 outwardly to zero at the tip. The cover is made in two parts 42 and 43, hinged at the tip as at 44 and engaging one another telescopically along their edges. Similarly the 38 cover may be made in sections which telescope longitudinally, and so provision may be made for extension and retraction of the blades. Since in Fig. II the spars 4 toward the bottom of the figure are shown to be 43 capable of lateral spread, it will be perceived that there must be allowance for this within the cover, and particularly at the tip of the blade. And upon this point it will suffice to say that the spars will ordinarily taper outwardly and be at their tips flexible in the plane of blade extent.

I claim as my invention:

1. A propeller or fan including a hub and a blade, the blade including in its structure a plurality of spars extensible and retractible relatively to the hub, and means for effecting relative movement of the spars in a direction transverse to the face of the blade, as they are extended and retracted.

5. A propeller including a hub and a blade, the blade including in its structure a plurality of spars extensible and retractible relatively to the hub, and means for effecting as the spars are extended and retracted relative movement of the spars in a direction transverse to the face of the blade, such relative movement being greatest at the base of the blade and diminishing thence outwardly.

6. A propeller or fan including a hub and a blade, the blade including in its structure

a plurality of spars extensible and retractible relatively to the hub, and means for effecting as the spars are extended and retracted, both a spreading of the spars laterally and a relative displacement of the 70 spars in a direction transverse to the face of the blade.

7. A propeller or fan including a hub and a blade, the blade including in its structure two spars with basal portions whose opposite edges as between the two spars are dissimilar in angular arrangement, the hub being provided with a radially opening pocket 75 in which the basal portions of the said spars are seated, one of the opposite edges of the orifice of the said pocket being defined by a cradle engaging the seated spars and adapted to rock in a direction transverse to the length of the seated spars, and means for extending and retracting the 80 said spars in their mounting in the hub.

8. A propeller or fan including a hub and a blade, the blade including in its structure two spars with basal portions whose opposite edges as between the two spars are dissimilar 85 in angular arrangement, the hub being provided with a radially opening pocket in which the basal portions of the said spars are seated, the orifice of the said pocket being defined on one side by a cradle 90 engaging the seated spars and adapted to rock in a direction transverse to the length of the spars, and on the opposite side by blocks 95 engaging the seated spars and adapted to rock in the direction of the length of the 100 spars, and means for extending and retracting the said spars in their mounting in the hub.

9. A propeller or fan including a hub and a blade, the blade including in its structure 105 two spars with basal portions whose opposite edges as between the two spars are dissimilar in angular arrangement, the hub being provided with a radially opening pocket in which the basal portions of said 110 spars are seated, one of the opposite edges of the orifice of the said pocket being defined by a cradle provided with a plurality of spar engaging blocks, the said cradle being adapted to rock in a direction transverse to the length of the seated spars, means 115 for effecting relative tipping in the direction of the length of the spars, of the blocks borne by said cradle, and means for extending and retracting the said spars in their 120 mounting in the hub.

10. A propeller or fan including a hub and a blade, the blade including in its structure two spars with basal portions whose opposite edges as between the two spars are dissimilar 125 in angular arrangement, the hub being provided with a radially opening pocket in which the basal portions of the said spars are seated, one of the opposite edges of the orifice of the said pocket being defined by a 130

cradle adapted to rock in a direction transverse to the length of the seated spars, the said cradle carrying wedge-shaped spar-spacing blocks.

- 6 8. A propeller or fan including a hub and a blade, the blade including in its structure two spars with basal portions whose opposite edges are as between the two spars dissimilar in angular arrangement, the hub being provided with a radially opening pocket in which the basal portions of the said spars are seated, one of the opposite edges of the orifice of the said pocket being defined by a transversely rocking cradle provided with 10 two longitudinally tipping spar-engaging blocks, means for extending and retracting the seated spars in their position in the orifice in the hub, and means for tipping the blocks with which the cradle is equipped, 15 one relatively to the other, as the spars are extended and retracted.

- 20 9. A propeller or fan including a hub and a blade, the blade including in its structure two spars with basal portions whose opposite edges are as between the two spars dissimilar in angular arrangement, the hub being provided with a radially opening pocket in which the basal portions of the said spars are seated, one of the opposite edges of the orifice of the said pocket being defined by a transversely rocking cradle provided with 25 two longitudinally tipping spar-engaging blocks, means for extending and retracting the seated spars in their position in the orifice in the hub, and means responsive to the rocking of the cradle for tipping the blocks with which the cradle is equipped, one relatively to the other.

- 30 10. A propeller or fan including a hub and a blade, the blade including in its structure two spars with basal portions whose opposite edges are as between the two spars dissimilar in angular arrangement, the hub being provided with a radially opening pocket in which the basal portions of the said spars are seated and from which the spars protrude, one of the opposite edges of the orifice of the said pocket being defined by a transversely rocking cradle provided with 35 two longitudinally tipping spar-engaging blocks, a rod rotatably borne by said cradle extending through the slots in the said blocks and equipped within each slot with an eccentrically mounted 40 individually adjustable disk, and means for extending and retracting the seated spars in their position in the said orifice.

45 in the said blocks and equipped within each slot with an eccentrically mounted disk, means for extending and retracting the seated spars in their position in said orifice and means for rotating said rod as the spars are extended and retracted.

50 11. A propeller or fan including a hub and a blade, the blade including in its structure two spars with basal portions whose opposite edges are as between the two spars dissimilar in angular arrangement, the hub being provided with a radially opening internally grooved pocket in which the basal portions of the said spars are seated and from which the spars protrude, one of the opposite edges of the orifice of the said pocket being defined by a transversely rocking cradle provided with two longitudinally tipping 55 spar-engaging radially slotted blocks, a bar rotatably borne by said cradle and bearing a crank arm engaged by the groove in the hub, the said rod extending through the slots in the said blocks and equipped within each slot with an eccentrically mounted 60 individually adjustable disk, and means for extending and retracting the seated spars in their position in the said orifice.

65 12. A propeller or fan including a hub and a blade the hub being provided with a radially opening orifice whose opposite edges are defined by pairs of tipping blocks the set of blocks which form one edge being borne in a transversely tipping cradle, the 70 blade including in its structure a plurality of spars which at their bases extend through the orifice in the hub and each spar between a pair of tipping blocks, the opposite and block-engaged edges of the bases of successive spars being disposed at varying angularity, means for controlling the tipping of the blocks which constitute the set on one side of the orifice, the edges of the bases of successive spars which engage the blocks 75 so controlled being disposed at varying angularity with respect to the mid line of the spar, and means for extending and re-80 tracting the seated spars in their position in the said orifice.

85 In testimony whereof I have hereunto set my hand.

LEE R. BUSHYAGER.
